UNITED STATES PATENT OFFICE.

JAMES R. KEARNEY, OF KANSAS CITY, MISSOURI.

WIRE PULLER.

Application filed August 8, 1922. Serial No. 580,510.

To all whom it may concern:

Be it known that I, JAMES R. KEARNEY, a citizen of the United States, residing at Kansas City, county of Jackson, and State 5 of Missouri, have invented a certain new and useful Improvement in Wire Pullers, of which the following is a full, clear, and exact description, such as will enable others skilled in the art to which it appertains to 10 make and use the same, reference being had to the accompanying drawings, forming part of this application.

My invention relates to wire pulling devices such as are generally used by linemen, although its use is not so limited as it may be used by any one who has occasion to exert a pull on a rope, wire, cable, or the like. In 15 wire pullers of this type, the wire is engaged between two parallel jaws which resemble the opposing faces of a parallel ruler, the two jaws being pivotally connected to each other on one side.

One object of my invention is to provide a more equal distribution of the strains on 20 the pivoting connections of the jaws by providing a double shear connection for the same. This construction will also prevent accidental release of the wire by the jaws due to movement of the wire transversely 25 of its length.

In order that the jaws may be applied to the wire transversely of the length of the latter, as is necessary where the wire is engaged at a point remote from its end, I desire 30 to make the jaw connections on one side movable away from the space between the jaws, and a further object of my invention is to adapt these connections to be moved into and out of engagement with one of the 35 jaws so as to clear the space between the jaws. The practical attainment of this object must be by means which can be operated with one hand, as also must the gripping and releasing of the wire irrespective 40 of the presence of the auxiliary connections referred to.

In the accompanying drawings, which illustrate a selected embodiment of my invention.

Figure 1 is a side view of my device showing the parts of the same in position to receive a cable between them.

Figure 2 is a similar view but showing the parts moved into cable clamping position.

Figure 3 is a fragmentary top view of the operating handle.

Figure 4 is a fragmentary side view taken on an enlarged scale and looking in the opposite direction from Figures 1 and 2.

Figure 5 is a vertical section on line 5—5 of Figure 4.

The lower jaw 1 of the device is connected to the upper jaw 2 by parallel levers 3 and 4. The latter have ordinary pivoted connections 5 to the lower jaw and extending beyond the upper jaw have ordinary pivotal connections 6 to a link 7. The connection between levers 3 and 4 and upper jaw 2 is a combined pivotal and sliding connection provided by the arcuate slotting of levers 3 and 4 to receive the jaw pivots 8 and 9. Pivots 8 and 9 have the portion of their periphery aligned with levers 3 and 4 toothed to mesh with the corresponding toothed portions 10 of the levers. The toothed portion 75 10 of the levers does not extend the full length of the slots but terminates far enough from the ends so that the lever may rotate on the stud to a limited degree at the end of the slot without further travel. The studs 80 8 and 9 extend through jaws 1 and 2 and on the side of the latter opposite to members 3 and 4 arms 11 and 12 are rigidly secured to the studs and are rotatable by the latter from the position shown in Figure 1 to that 85 shown in Figure 2, or vice versa.

The ordinary studs pivotally connecting the lower jaws of the levers also extend through the lower jaw, and on the opposite side thereof, form shouldered pins 13 adapted to receive the notched ends 14 of jaws 11 and 12, when the latter are rotated to the 90 position shown in Figure 2.

To provide the relative sliding movement between levers 3 and 4 and upper jaw 2 necessary to rotate studs 8 and 9 is the function of an element 15 and handle 16. The latter is slidingly and pivotally mounted upon upper jaw 2 and is pivotally connected to link 7 by element 15. A single pin 17 through element 15 and handle 16 and a slot 18 in jaw 2 insures the desired connection of these members. A rigid lug 19 projecting from element 15 is adapted to engage a corresponding projection 20 on lever 4 and push the latter from the position shown in Figure 2 to that shown in Figure 1.

When a wire or cable A is inserted between the jaws transversely of its length as may easily be done when the parts are in the 110 position shown in Figure 1, one hand can easily grasp the handle 16 and by pressing

the thumb against the end of upper jaw 2, the parts are shifted to the wire clamping shown in Figure 2 and in which studs 8 and 9 have been rotated to the opposite end of 5 the lever slots, their rotation also rotating arms 11 and 12 to the position in which they engage studs 5 on lower jaw 1. Any pull now exerted upon handle 16 tightens the grip of the jaws on the wire as such pull 10 is along member 15, link 7, and on the upper ends of levers 3 and 4 tending to turn the latter on pivots 8 and 9 so as to bring lower jaw 1 still closer to upper jaw 2.

To release the jaws, handle 16 is turned 15 downwardly upon its pivot 17 and pressure applied in a direction opposite to that of the pull which will first turn levers 3 and 4 upon studs 8 and 9 until lug 19 engages projection 20 when the levers will be slid along upper 20 jaw 2 to the position shown in Figure 4.

The device is simple and rugged in construction and will tightly grip any size wire within its maximum capacity. The pins which transmit the stresses applied to the 25 jaws by the lever are placed in double shear by means of arms 11 and 12 and the latter, when the puller is in operation, enclose the wire A and prevent possibility of its slipping out of the jaws sideways, thereby effecting 30 the sudden release of the wire puller and the possible injury to the linemen.

Various modifications in the details of my invention may be made without departing from the spirit thereof as expressed in 35 the appended claims.

I claim:

1. In a wire puller, parallel gripping jaws, a lever on one side of said jaws permanently pivoted to each of said jaws, and a 40 lever on the other side of said jaws permanently pivoted to one of said jaws and adapted to pivotally engage the other of said jaws or to be disengaged therefrom automatically when said jaws are closed or unclosed, respectively.

2. In a wire puller, parallel gripping jaws, levers on one side of said jaws pivoted to each of said jaws, a handle connected to said levers, arms on the other side of said 50 jaws pivoted to one of said jaws, studs on the other of said jaws, and means for turning said arms into engagement with said studs operated automatically upon relative movement of said handle and one of said jaws.

3. In a wire puller, a lower jaw, a parallel upper jaw, a handle slidably mounted on said upper jaw, parallel levers pivotally connected to said lower jaw, slidably and pivotally connected to said upper jaw, and extending beyond the latter, a link pivotally connecting the extending portions 60 of said levers, a member pivotally connect-

ing said link and said handle, and wire engaging elements operable by sliding movement of said handle on said upper jaw.

4. In a wire puller, upper and lower parallel jaws, studs on each of said jaws, parallel levers pivoted at their lower ends on said studs on said lower jaw, a link pivoted to said levers at their upper ends, each of said levers having a toothed arcuate slot intermediate its ends meshing with teeth formed on said studs on said upper jaw, and a handle secured to said link.

5. In a wire puller, upper and lower parallel jaws, studs on each of said jaws, those on the upper jaw being rotatable, parallel levers pivoted at their lower ends on said studs on said lower jaw, a link pivoted to said levers at their upper ends, each of said levers having a toothed arcuate slot intermediate its ends meshing with teeth formed on said studs on said upper jaw, arms rigidly formed on the toothed studs on said upper jaw and notched to engage the studs on said lower jaw when the toothed studs are rotated, a handle slidable on said upper jaw, and an element connecting said handle and said link.

6. In a wire puller, parallel jaws, a lever located at one side of said jaws pivoted to one jaw, and slidably pivoted to the other jaw, an arm located on the other side of said jaws and adapted to lie parallel therewith or to span the space between said jaws, and gearing between said lever and said arm whereby slidable movement of said lever on one of said jaws rotates said arm from one of its described positions to the other.

7. In a wire puller, parallel jaws, a lever located at one side of said jaws, pivoted to one jaw and slidably pivoted to the other jaw, an arm located on the other side of said jaws and adapted to lie parallel therewith or to span the space between said jaws, an operating handle slidable on the latter-mentioned jaw, an element pivotally connecting said lever and handle and adapted to engage and move said lever along said jaw as said handle is slid in one direction on said jaw, and gearing between said lever and said arm whereby such movement of said lever rotates said arm from one of its described positions to the other.

8. In a wire puller, parallel gripping jaws, a lever on one side of said jaws permanently pivoted to each of said jaws, and a lever on the other side of said jaws permanently pivoted to one of said jaws and adapted to pivotally engage the other of said jaws automatically when said jaws are closed.

In testimony whereof I hereunto affix my signature this 24th day of July, 1922.

JAMES R. KEARNEY.
